TYPEWRITING MACHINE

William F. Helmond, Clinton, Conn., assignor to
Underwood Elliott Fisher Company, New York,
N. Y., a corporation of Delaware

Original application September 14, 1937, Serial
No. 163,739. Divided and this application June
29, 1940, Serial No. 343,112

7 Claims. (Cl. 197—80)

This invention relates to typewriting machines, and, with respect to certain more specific features thereof, to case shifting mechanism and key controls therefor. This application is a division of my application Serial No. 163,739, filed September 14, 1937, now Patent No. 2,226,931, issued December 31, 1940.

One object of the invention is to provide a simple, cheaply manufactured, smoothly operating key-operable case shift mechanism.

It is another object of the invention to provide, in association with two keys that are operable to case-shift a body, a simple, reliably operating device which will normally detain one of the keys upon being depressed, and which device is rendered ineffective by the depression of the other key.

A further object of the invention is to provide simple and reliable operating spring-pressed means to detain widely separated lock-keys upon being operated to case-shift a body, the means being adapted to be rendered ineffective by operating other widely separated keys so as to free the lock-keys to allow restoration of the case-shift body. These last-mentioned keys are also operable to case-shift said body while the lock-keys are in normal position. In any event they will return immediately to normal position upon being released.

Another object of the invention is to provide a key operable case-shift mechanism having an extremely light and smooth key-touch.

Further objects and advantages of the invention will readily become apparent as the description of the invention proceeds.

In the embodiment of the invention shown, a case-shift lock-key is operable to case-shift a body and is automatically detained in operated position by a spring-pressed lock-pawl that is pivotally mounted on the lock-key and adapted to engage a machine frame shoulder. Another shift-key is also operable to case-shift said body but does not carry a lock-pawl and, therefore, re-assumes its normal position immediately after being released. The latter shift-key may also be operated to release the lock-pawl on the case-shift lock-key and a portion thereof is for this purpose engageable with the lock-pawl to throw it to ineffective position. There is a case-shift key and a case-shift lock-key at each lateral end of the keyboard and these keys are respectively interconnected for operation in unison. Preferably each of the case-shift lock-keys carries a lock-pawl and each of the interconnected case-shift keys is engageable with one of said lock-

paws to move it to ineffective position. It follows, therefore, that the depression of either case-shift key will release both latches on the case-shift lock-keys to allow their return to normal position.

In the accompanying drawings:

Figure 1 is a transverse sectional view through a machine embodying the invention, taken on the front and back radial plane and showing the type bar segment in normal upper position for typing in

10 lower-case type.

Figure 2 is a perspective view of the entire case-shift mechanism in normal position, with the type bar segment in normal raised position for typing in

15 lower-case type.

Figure 3 is a fragmentary perspective view similar to Figure 2, showing the case-shift lock-keys depressed and held by lock-pawls to detain the case-shift body for typing in upper-case.

20 Figure 4 is a view similar to Figures 2 and 3, showing the case-shift levers in operated position and the lock-pawls on the case-shift lock-keys moved to ineffective position by the case-shift levers.

25 The type-action illustrated in the drawings is similar to that shown and described in my Patent No. 2,072,878, dated March 9, 1937. The type-action includes a system of key-levers 12, fulcrumed adjacent the back of the machine, the key-levers

30 being flexibly joined by links 13 to a series of sub-levers 14 pivoted on a fulcrum-rod 15, carried in a cross-bar 16 mounted on the side plates 17 comprising the frame of the machine. The sub-levers 14 actuate a system of type-bars 18 by means of

35 pull-rods 19 flexibly joining the free end of each sub-lever 14 to a drive arm 20 of the type-bar 18. The series of type-bars 18 are pivotally mounted in a segment 21 for swinging toward a common printing point on a platen 22, the latter being

40 guided for letter-space movement, by a platen-carriage 23 riding in a trackway 24 extending between the side plates 17.

45 The segment 21, together with a segment-frame 25 to which it is secured, constitutes a case-shiftable body. The segment-frame 25 has depending members or arms 26 wherein a rock-shaft 28 is journaled in bearings 27, the shaft 28 extending laterally to the side plates 17 of the machine and carrying at each end an anti-friction roller 29 that is guided between vertical

50 guide-faces 30 in the side-plates 17.

The segment-frame 25 has at each lateral upper end a raceway 36 flanked by a companion raceway on the frame, not shown, and balls 33 cooperate with these companion raceways to

guide the segment-frame 25 at its upper region.

As will be described hereinafter in detail, the rock-shaft 28 accomplishes several functions, namely, that of coordinating the action of the two case-shift lock-key levers 62 located at opposite sides of the machine, and enforcing equal movement of both ends of the segment-frame 25.

At each extremity, the rockable shaft 28 has associated therewith an articulated leverage-train 55, comprising a first arm 56 affixed to the shaft 28, and a second arm 57 fulcrumed at 58 on the main frame, and articulated to the first arm 56, so as to constitute a toggle joint. Fulcrum 58 is disposed on a line defining the path of travel of the segment-frame 25 in case-shifting and below same, so that when the arms 56 and 57 are aligned, one with the other, the segment 21 and associated type-bars 18 are maintained in raised position thereby for lower-case typing. As arm 57 is caused to swing, the toggle-joint or leverage-train 55 is unlocked and folded to lower the segment assembly to upper-case typing position.

Each arm 57 forms part of a bell-crank also including a drive arm 52, each of which drive arms is flexibly joined by a link 60 to an arm 61 of a shift-lock lever 62. Springs 59, attached to the lock-levers 62, urge the latter to normal position so that said toggle joints 55 are normally straight and hold said segment 21 and segment-frame 25 in lower-case typing position, as seen in Figures 1 and 2. Each shift-lock lever 62 is fulcrumed on the sub-lever fulcrum-rod 15 and extends forwardly of the machine, terminating in a shift-lock key 63. Each shift-lock lever 62 has associated therewith a shift-lever 64, also fulcrumed on rod 15 and carrying a shift-key 65 at its free end. Shift-lever 64 includes a lug 66 extending therefrom to overlie the lever 62 so that upon depressing the shift-lever 64, the lock-lever will move therewith, although the shift-lock lever 62 may be actuated independently of the shift-lever 64. The return spring 59 is anchored on the machine, its end being joined to a depending member of the lock-lever arm 61 whereby to urge the toggles 55 to aligned condition so that same hold the segment raised, the toggles 55 being stopped at aligned setting by the engagement of the lock-lever 62 with a guide-plate 74 or other member of the machine.

Due to the normally straightened condition of the toggles, the initial leverage of the keys 63, 65 to case-shift the segment frame 25 is extremely great, consequently, touch of these keys is extremely light and pleasing. The segment-frame 25 is shown in Figures 3 and 4 as having been shifted respectively by the depression of the case-shift lock-key and the case-shift key. One or more stops, not shown, are provided to limit the case-shift movement of the segment-frame.

It will be noted from the foregoing that the rockable shaft 28, by operatively connecting the arms 56, functions to coordinate the actions of both of the toggles 55 whereby lowering or raising power thereof is imparted equally to both extremities of segment 21, Figure 2. Since each toggle 55 is operably associated with a corresponding shift-lock lever 62, the actions of the respective levers 62 are also coordinated. The rockable shaft 28, connecting the two arms 56 of the toggles 55 together, is rotatably carried in the segment-frame 25, at a relatively high elevation in the machine, thereby affording ade-

quate space underneath for mechanisms such as the rearwardly extending key-levers.

A shift-lock 67 is provided to lock lever 62 down, the lock 67 being so associated with the respective shift-levers 62, 64, that when both levers move together, as by depressing lever 64, the lock is ineffective, and inversely, as the shift-lock lever 62 moves independently of the shift-lever 64, the lock 67 is allowed to engage. Lock 67 comprises a lock pawl 68 presenting a bell-crank pivotally mounted on the lock-lever 62 and urged by a spring 69 to swing into locking engagement with a detent-shoulder 70, but normally prevented from so doing by the engagement of a lateral lug 71 of pawl 68, with a pad 72 on the shift-lever 64.

Figure 3 illustrates the operation of the mechanism in locking the segment down by depressing the lock-lever 62, the lock pawl 68 having been allowed to swing into engagement with the detent 70 by the tendency of the lug 71 to move away from the pad 72, thereby releasing the pawl 68 to permit its spring 69 to actuate the pawl into engagement with the detent 70. This action is due to the relative positions of the lock-lever 62 and the shift-lever 64 which, during depression of the lock-lever 62, are moved apart and consequently release the pawl 68 to engage the detent.

In releasing the lock 67, the reverse operation takes place, the lock being released by depressing the shift-lever 64 during which its pad 72, engaging the lateral lug 71, swings the pawl 68 free of the detent 70, the pawl releasing at the instant the lug 66 reaches the depressed lock-lever 62. The shift-lever 64 thus assumes the power of the return spring 59, the latter tending to raise the segment 21, Figure 5. Shift-lever 64 is now permitted to rise, being manually controlled, and the segment 21 returns to its normal raised position.

A particular advantage of the novel case-shift lock 67 is that both the shift-lock key 63 and the shift-key 65 are at a constant elevation at the time the function of either is required. As is usual in case-shift mechanisms, the shift-lock key is locked down during the interval at which the segment is locked down for upper-case printing, but, in such machines the shift-key is also lowered. In the present invention the shift-key 65 remains at normal position although the shift-lock key 63 be depressed and the operator may therefore accustom herself to finding the shift-key 65 at the same elevation at all times. Furthermore, the work of releasing the pawl 68 from its detent 70 is minimized since the releasing is effected during the entire down-stroke of the shift-lever 64. This improved operation makes for an appreciably light touch and smooth action of the shift-lever 64 in its unlocking function, the same acting without jar, by assuming the load of the segment mass, effective by the return spring 59, at the instant of release of lock 67.

The respective actions of each shift-lever 64 are coordinated by a rockable bail 75 trunnioned on brackets 76 adjustably affixed to the guide-plate 74 by screws 77 disposed in slots therein. The rockable bail 75, extending laterally of the machine, includes a forked arm 78 at each end thereof which engages a pin 79 carried on a member 80 of the shift-lever 64. It will be noted that the detent 70, co-operating with the lock 67 forms part of the bracket 76, so that both the detent and the journal of the bail 75 are

adjustable simultaneously. In the event that lowering of detent 70 is required in regulating the shift mechanism, the lower locked position of lever 62 necessitates a greater drop for shift-lever 64 to release the lock 67, which increase is accommodated by lowering the bracket 76.

The work of the return springs 59, in restoring the type-bar segment 21 to normally raised position in co-operation with the toggles 55, is supplemented by balancing springs 82 which have the effect of resiliently sustaining the segment 21. Springs 82 are anchored at their upper ends to a fixed portion of the machine and are secured to studs 83 projecting from the segment-frame 25, Figures 1 and 2. The balance springs 82 may be so tensioned as to yieldably sustain the entire mass of the type-bar basket, the weight of which is supported by the segment-frame 25, the effect being to substantially reduce the effort required to move the segment in case-shifting.

It will be noted that at the depression of either shift-lock lever 62 relatively to its companion shift-lever 64, the other shift-lock lever 62 is also depressed relatively to its companion shift-lever 64, since both of said levers 62 are operatively connected by means of the cross-shaft 28. Hence both of the locking pawls 67 are caused to move to effective position under their detents 70, as in Figure 3, at the depression of either shift-lock lever 62. The depression of either shift-lever 64 for the purpose of releasing the companion locking pawl 67 also serves, by means of the cross-shaft 75, to depress the other shift-lever 64 thereby to release also the locking pawl 67 associated with the latter. It is to be understood that one of the lock pawls may be eliminated, if desired.

What is claimed is:

1. In a case-shift mechanism for typewriting machines, two widely spaced case-shift keys, a case-shift lock-key operable independently of said two case-shift keys, a lock-member pivoted on said lock-key, detent means adapted to be engaged by said lock-member to detain said lock-key upon operation, means for influencing said lock-member to engage said detent means, an interconnection between the said two case-shift keys, and means to render said lock-member free from said detent means by the operation of either of said two case-shift keys.

2. In a case-shift mechanism for typewriting machines, two widely spaced case-shift keys, a case-shift lock-key operable independently of said two case-shift keys, a lock-member movable on said lock-key, detent means adapted to be engaged by said lock-member to detain said lock-key upon operation, means for influencing said lock-member to engage said detent means, a connecting bail between the said two case-shift keys, and means to render said lock-member free of said detent means by the operation of either of said two case-shift keys.

3. In a typewriter having a case-shiftable body, a case-shift lock-key having an operative connection for case-shifting said body, two widely spaced case-shift keys, a lock-member movably

5 mounted on said lock-key, a detent adapted to be engaged by said lock-member to detain said lock-key upon operation, means influencing said lock-member to engage said detent, an operative connection between the said two case-shift keys, means to render said lock-member free of said detent by the operation of either of said two case-shift keys, and means providing for operation of said case-shift lock-key by said case-shift keys but rendering said case-shift lock-key operable independently of said case-shift keys.

4. In a case-shift mechanism for typewriting machines, two widely spaced case-shift keys, a case-shift lock-key adjacent to each one of said case-shift keys, means connecting the lock-keys to move together, means connecting the case-shift keys to move together, a lock-member movably mounted on at least one of said lock-keys, detent means adapted to be engaged by said lock-member to detain the lock-keys upon operation, means influencing said lock-member to engage said detent means, and means for forcibly freeing said lock-member from said detent means by the operation of said case-shift keys.

5. In a case-shift mechanism for typewriting machines, in combination, a shift-lever, a lock-lever, substantially in juxtaposition to said shift-lever, one of said levers having a projection providing for the operation of said lock-lever by said shift-lever but rendering the lock-lever operable independently of said shift-lever, and lock means for releasably detaining the lock-lever upon operation, comprising a pivoted pawl having a projection underlying said shift-lever, a detent engageable by said pawl, and spring means associated with said pawl and urging it toward said detent, the pawl being normally held from said detent by said shift-lever and being urged by said spring means to engage said detent upon depression of said lock-lever.

6. In a case-shift mechanism for typewriting machines, two spaced case-shift lock-keys interconnected to move in unison, lock-means for releasably detaining said lock-keys upon operation, detent-means engageable by said lock-means, spring-means urging said lock-means to engage said detent-means, and a pair of spaced case-shift keys interconnected to move in unison and operatively connected with said lock-means so that operation of either of said case-shift keys renders the lock-means ineffective.

7. In a typewriter having a case-shiftable body, toggle-means operable to case-shift said body comprising widely separated toggle-linkages interconnected for operation in unison, a case-shift lock-key connected to each said toggle-linkages, a lock-member carried by each of said lock-keys, detents engageable by said lock-members in the operated position of said toggle-means, means resiliently urging said lock-members to engage said detents, and other case-shift keys interconnected for operation in unison and having each an operative connection with one of the lock-members, said operative connections being adapted to render said lock-members released upon operation of the last said keys.

WILLIAM F. HELMOND.
